UNITED STATES PATENT OFFICE.

WILLIAM G. WALTER, OF PITTSBURG, PENNSYLVANIA, ASSIGNOR TO THE THOMPSON GLASS COMPANY, (LIMITED,) OF SAME PLACE.

DESIGN FOR A DISH.

SPECIFICATION forming part of Design No. 19,764, dated April 15, 1890.

Application filed February 25, 1890. Serial No. 341,754. Term of patent 3½ years.

To all whom it may concern:

Be it known that I, WILLIAM G. WALTER, of Pittsburg, in the county of Allegheny and State of Pennsylvania, have invented and produced a new and original Design for Glassware, of which the following is a specification, reference being had to the accompanying drawing, forming part thereof.

The leading feature of my design consists of a dish having thereon a figure representing a lady tourist arrayed in traveling costume, with a cap on her head and a satchel in her hand, said tourist being entirely surrounded by a zone or belt having thereon an inscription.

The accompanying drawing represents a glass dish, the center of which consists of an oval flat surface A, upon which is formed in cameo or intaglio a representation and figure of the tourist B above described, which is surrounded by a belt or band C, located a short distance from said figure and provided with a buckle D. On this belt and around the same is formed an inscription. The bottom of the dish, upon which is a representation of a lady tourist, consists of a flat and plain surface A, from which arise the sides of the dish, inclining upwardly and outwardly in a series of flutes or corrugations E, which are longer in the middle of the dish and gradually grow shorter toward each end of the plain bottom or surface, where they terminate. The extending portion F of the dish outside the belt may be left plain or formed with an ornamental surface of any suitable sort or configuration.

What I claim is—

The design for a dish or similar article of glassware herein shown and described.

In testimony whereof I have hereunto set my hand this 17th day of February, A. D. 1890.

WILLIAM G. WALTER.
